ORTHODONTIA APPLIANCE

Harry J. Russell, Toronto, Ontario, Canada, assignor to Baker & Company, Inc., Newark, N. J., a corporation of New Jersey

Application October 31, 1934, Serial No. 750,835

1 Claim. (Cl. 32—14)

This invention relates generally to orthodontia appliances, and more particularly to a device for attaching an arch-bow to selected teeth of the dental arch for the purpose of moving or straightening the teeth.

One object of the invention is to provide a device of this character which shall include a body portion for attachment to a tooth band and constructed to permit the arch-bow or wire to be applied thereto in approximately the plane of the dental arch, in combination with removable clamping means for either positively clamping the wire in the body portion against movement relative thereto or to hold the wire against lateral displacement from the body portion and free for movement longitudinally of itself. Such a device will to a great extent eliminate the necessity for the use of ligatures because the arch-bow can be accurately bent for attaching to particular misplaced teeth and then easily inserted in the locking device. Furthermore, the positive clamping of the arch wire in the lock eliminates the necessity for soldering of stops on the arch wire at the anchor teeth since the lock may be applied to an anchor tooth and the arch-bow can be adjusted to the desired position by sliding through the lock, after which the wire can be positively clamped in the lock.

Another object of the invention is to provide an orthodontia lock of this character wherein the arch wire may be attached to the lock in such a way as to make possible the exertion of pressure or tension on a tooth in any direction, whereby complete control of rotation of molars and distal or mesial tipping of teeth may be easily accomplished.

A further object is to provide an orthodontia lock of the general character described especially adapted for use with arch wire of rectangular cross-section so that the wire can be positively clamped in the lock at all four sides of the wire to prevent rotation of the wire, whereby a tooth may be rotated or tipped in various directions without the necessity for springs or other extraneous pressure; although the invention contemplates a lock which may be used with arch wire of any cross-section shape.

Another and highly important object of the invention is to provide such a lock which shall be of minimum size consistent with the required strength so as to cause a minimum of irritation in the mouth, and thus to form the lock of simply a body portion having a slot to receive the arch wire, and a clamping screw plug for holding the wire in said slot.

A lock of this character is extremely small, the screw plug being about three sixty-fourths of an inch in diameter, and to make it possible to practically use such a lock an easy, sure and quick method of handling the plug is necessary. Accordingly another object is to provide a novel and improved construction and combination of the plug and a tool, whereby the plug can be picked up, carried and manipulated by the tool by simple pressure of the tool against the plug.

Other objects of the invention are to provide an orthodontia lock which shall constitute a minimum of projection from the teeth so as to cause a minimum of irritation in the mouth of the patient; to provide an orthodontia lock which shall be simple and inexpensive in construction, strong and durable, and which shall simplify orthodontia operations so that it shall be possible to perform such operations in a minimum of time and with a minimum of discomfort to the patient; and to obtain other advantages and results as will be brought out by the following description.

Referring to the accompanying drawing in which corresponding and like parts are designated throughout the several views by the same reference characters,

Figure 1 is a plan view of a dental arch having an orthodontia appliance embodying my invention applied thereto.

Figure 2 is an enlarged front elevation of one of the orthodontia locks embodying the invention applied to a tooth.

Figure 3 is a transverse vertical section of the view on the line 3—3 of Figure 2.

Figure 4 is a composite view of the lock and the tool for operating the clamping screw plug.

Figure 5 is a perspective view of the lock showing the body portion and the clamping plug in separated relation.

Figure 6 is a front elevation of a form of the lock especially adapted for use on molar teeth.

Figure 7 is a horizontal sectional view through several teeth having locks attached thereto showing the manner of using the locks, and,

Figure 8 is a front elevation of several teeth with locks attached thereto illustrating the adaptability of the lock to difficult orthodontic operations.

Specifically describing the illustrated embodiment of the invention, the orthodontia lock comprises a body portion 1 which is preferably in the form of a block of metal having curved sides to eliminate angular portions which might irritate the tissues of the mouth, said block having a

transverse slot 2 and an axial screw threaded opening 3 extending transverse of the slot and of a diameter substantially greater than the width of the slot, the axis of the opening preferably lying in the longitudinal medial plane of the slot. The slot 2 is preferably rectangular and of a width to nicely receive an arch wire 4 that is approximately square in cross section. For holding the arch wire in the slot, a screw plug 5 is provided to fit the opening 3, and the plug is adjustable in the opening so as to either positively clamp the arch wire against any movement, as shown in Figure 3 of the drawing, or the plug may be screwed into the opening 3 in slightly spaced relation to the arch wire to hold the wire against displacement from the slot but permit longitudinal movement of the wire.

Preferably the plug 5 has a central opening or recess 6 to cooperate with a tool 7 for handling and manipulating the plug. As shown, this opening is noncircular and may be either square as shown in Figures 2 and 4, or oblong rectangular as shown in Figure 5. The tool 7 has an end portion 8 corresponding in shape and size to the opening 6 in the plug but preferably tapered so as to frictionally engage the walls of said opening when the tool is pressed into the opening, whereby the plug can be attached and detached from the tool and carried to and from the mouth of the patient and screwed into or removed from the body portion of the lock, easily, quickly, and surely. If desired, the plug and tool 7 may be made of magnetic material, and one thereof may be magnetized to make the connection of the tool to the plug more positive.

In use of the orthodontic lock, the body portion 1 is secured, preferably by soldering, to a tooth band 9 which is connected to a tooth 10 involved in the contemplated operation. The block 1 is applied to the tooth band with the mouth of the slot 2 facing labially or buccally according to the position of the tooth, so that the medial plane of the slot is approximately parallel to the plane of the dental arch, and the arch wire may be applied to the slots in a direction generally parallel to the arch, for example, as shown in Figure 8 of the drawing. The plugs 5 are of course initially removed from the blocks 1 and the arch wire is bent to correspond to the positions of the teeth to be operated upon and to exert the desired tension or pressure on the teeth, after which the arch wire may be slipped into the slots of the respective blocks. Then the plugs 5 are screwed into place, either into tight clamping relation to the arch wire or loosely to permit sliding of the blocks relative to the arch wire.

One of the locks may be applied to each anchor tooth 11 as shown in Figure 1 for securing the ends of the arch wire, and obviously longitudinal adjustments of the arch wire may be made by sliding the wire through the slots 2 and then clamping the wire in the adjusted positions by the plugs 5. Preferably the locks used on the molar teeth have somewhat broader bases on the blocks than the locks used on the anterior teeth, i. e., bicuspids and incisors, and as shown in Figure 6, winged extensions 12 are formed on the blocks for the molar locks to distribute the tension and pressure through the blocks over a greater area of the teeth.

With reference to Figures 7 and 8, it will be observed that my lock makes possible the accomplishment of difficult tooth moving operations, simply, in a minimum of time, and with

minimum discomfort to the patient. The ease of applying the arch wire to the locks so that the arch wire can be bent as desired to exert the necessary pressure or tension, in combination with the adjustability of pressure afforded by the plugs 5 in slots 2, eliminates to a great extent the necessity for ligatures. Molar rotation and distal and mesial tipping of the teeth may also be easily accomplished. As shown in Figure 7, the arch wire may be disposed diagonally of the slot 2 so that the plug will engage the wire at one point diagonally opposite the engagement of the wire with the base of the slot 2 to exert a rotative action on the tooth at A, and the plug can be repeatedly adjusted to adjust the pressure and compensate for movement of the tooth. In other cases, the arch wire may be slightly bent or looped in the medial plane of the slot so that the plug engages the base of the loop to exert longitudinal pressure on the wire in opposite directions by flattening of the loop under the pressure of the plug. This operation is illustrated at B in Figure 7 of the drawing. This separation is greatly facilitated by the fact that the wire may be tightly clamped against longitudinal movement in the locks on the teeth at either or both sides of the tooth at which the loop in the wire is located. The operation of teeth under the spring pressure of the wire is facilitated by this positive clamping of the wire in the locks as indicated by the two middle teeth illustrated in Figure 8.

While I have shown the lock as especially adapted for use with arch wire that is rectangular in cross section, obviously arch wire of any cross-section shape may be used in connection with the lock.

The facility afforded in handling the plug 5 is highly important, since these plugs are of necessity minute. Moreover, it is highly desirable that the locks constitute a minimum of projection from the teeth to avoid irritation of the tissues of the mouth, and the particular method of handling the plugs makes it possible to form them of a minimum size consistent with the clamping pressure required for locking the arch wire in the blocks 1, so that the over all size of the locks is reduced to the minimum.

Other possibilities of use and variations in the relations of the wire to the slots will occur to those skilled in the art.

It will be understood by those skilled in the art that the specific structure of the lock may be modified and changed without departing from the spirit or scope of the invention, and therefore I do not desire to be understood to be limiting myself in the construction of the lock except as required by the following claim when construed in the light of the prior art.

Having thus described my invention, what I claim is:

An orthodontic appliance comprising a tooth band secured to a tooth, a lock including a block secured to said tooth band having a transverse slot the longitudinal medial plane of which is approximately perpendicular to the axis of said band, said block also having a screw threaded recess extending transversely of said slot with its axis approximately in said medial plane of said slot, an arch bow in said slot, and a screw plug in said recess holding said arch bow in said slot and having a non-circular opening to frictionally receive a tool for handling and rotating the plug.
